Specification for Design.

Patented Apr. 26, 1921.

Application filed November 23, 1920. Serial No. 426,090. Term of patent 14 years.

To all whom it may concern:

Be it known that I, SAMUEL C. LORD, a citizen of the United States, residing at Milton, in the county of Norfolk and Commonwealth of Massachusetts, have invented a new, original, and ornamental Design for Desk-Thermometers, of which the following is a specification, reference being had to the accompanying drawing, forming part thereof.

Figures 1 and 2 represent perspective and side elevations of the thermometer, showing my new design.

I claim:

The ornamental design for a desk thermometer, as shown.

SAM'L C. LORD.
